[57] CLAIM

The ornamental design for a keg cooling pad, as shown and described.

DESCRIPTION

FIG. 1 is a front, top and left edge perspective view of a keg cooling pad showing my new design;

FIG. 2 is a back, bottom and right edge perspective view thereof; and,

FIG. 3 is a perspective view thereof shown in a closed position, the keg shown in broken line for illustrative purposes only and forming no part of the claimed design.

1 Claim, 2 Drawing Sheets

FIG. 3
